(57) **CLAIM**

(21) Appl. No.: **29/632,315**

The ornamental design for a display screen or portion
thereof with a graphical user interface, as shown and
described.

(22) Filed: **Jan. 5, 2018**

DESCRIPTION

(51) LOC (11) Cl. **14-04**

The patent or application file contains at least one drawing
executed in color. Copies of this patent or patent application
publication with color drawing(s) will be provided by the
Office upon request and payment of the necessary fee.
The FIGURE is a front view of a display screen or portion
thereof with a graphical user interface showing the new
design.
